SWITCH POINT PROTECTOR

Charles M. Staples, Houston, Tex.

Application January 23, 1939, Serial No. 252,451

6 Claims. (Cl. 246—448)

My invention relates to new and useful improvements in railway switches.

An important object of my invention is to provide means supplementing the usual switch throwing mechanism, for the purpose of locking the switch point against the main rail when the switch is closed.

Another object of my invention is to provide a supplementary switch lock that is automatic in its closing and locking action.

Still another object of my invention is to provide a supplementary switch lock that is adaptable to all sizes and weights of stock rails.

Yet another object of my invention is to provide a supplementary switch lock that is simple in construction, efficient in operation and inexpensive to manufacture.

Other objects and advantages of my invention will be apparent during the course of the following description.

In the accompanying drawing, forming a part of this specification, and in which like numerals are employed to designate like parts throughout the same,

Figure 1 is a plan view of my device, showing its association with a conventional railway track, switch points and switch.

Figure 2 is a transverse sectional view, taken on the line 2—2 of Figure 1, showing the rail and switch point in a closed position, and with my device in locked engagement therewith.

Figure 3 is a view similar to Figure 2, but showing my device in the open position.

Figure 4 is a view similar to Figure 2 but showing the rail and switch point in the open position.

Figure 5 is a plan view of my device, and

Figure 6 is an end elevation thereof.

In the drawing, wherein for the purpose of illustration, is shown a preferred embodiment of my invention, the numeral 10 designates a pair of railway rails mounted upon the ties 11 some of which are extended at one end thereof as shown at 12 to support the conventional switch opening mechanism 13. The ends of the switch points are shown at 14 and are of the usual construction.

My device comprises a substantially rectangular latch plate 15 adapted to extend underneath the rail 10 and with the outer end 16 thereof terminating in an upwardly disposed flange 17 adapted to be positioned in abutting relation with the outer longitudinal edge of the rail 10. A leaf spring 18 is formed with a horizontally disposed end 19 and a vertically disposed end 20 which integrally connects to the

horizontally disposed end 19 by an elevated horizontal middle portion 21 and angularly disposed portion 21'. The bolt 22 is received within an elongated slot 23 provided in the latch plate 15 so that the leaf spring 18 may be longitudinally adjustable thereon. The vertically disposed portion 20 of the leaf spring is bolted or otherwise secured to the switch point 14. Both the leaf spring 18 and the latch plate 15 are resilient in their action to withstand the vibrations and stresses to which they will be subjected at frequent intervals due to the passing of trains on the rails 10, however, the combined resilient action is sufficiently great to securely hold the rail and switch point in locked engagement. The end 16 of the latch plate is formed with an inwardly extending slot 24, and securely fastened to the underside thereof is an inverted U-shaped bracket 25 which terminates at its open end in horizontally disposed extremities 26 welded or otherwise secured to the underside of the plate 15. Fulcrumed in the bracket 25 is a lever member 27 which is formed with right angularly disposed arms 28 and 29. The arm 29 is adapted to extend angularly above the base of the rail 10 and terminates in a flared foot pedal 30. The end of the arm 28, disposed at right angles thereto, is received within the slot 24 and contacts the underside of the rail 10.

It is well known that continued wear on the usual switch throwing mechanism, and accidents resulting in the bending of any of its connections, or breakage of certain of its fastenings will permit the switch point to stand slightly away from the main rail when the switch is closed, and that a sharp flanged wheel may readily spread the switch with disastrous results. My device is adapted to prevent this from occurring by securely fastening the leaf spring 18 on the plate 15 in the properly adjusted position and with the vertically disposed end of the latch plate 15 in close frictional engagement with the longitudinal edge of the rail 10.

Normally a switchman coming to the switch stand 13 for the purpose of opening the switch will first place his foot on the pedal 30 to depress the same which will cause the angularly disposed arm 28 to bear against the underside of the rail 10 and to disengage the flange 17 from the edge of the rail 10. He can then open the switch by means of the switch stand and its appurtenances. As long as the switch stand is open the supplementary catch is in a non-locking position as shown in Figure 4, however, as soon as the switch is closed, the flange 17 of the latch plate 15 will

automatically move into the locking position, as shown in Figure 2, thereby securing the switch point 14 against the rail 10.

It is to be understood that the form of my invention, herewith shown and described, is to be taken as a preferred example of the same, and that various changes in the size, shape and arrangement of parts may be resorted to without departing from the spirit of my invention, or the scope of the appended claims.

Having thus described my invention, I claim:

1. A railway switch point lock comprising a latch plate extending under the rail and terminating in a vertically disposed flange which is formed with an inwardly extending slot, said flange being adapted to be positioned in abutting relation with the outer edge of the rail; a companion element having one end adjustably secured to the said latch plate and terminating at its opposite end in a vertically disposed portion fastened to the switch point; an inverted U-shaped bracket secured to the said latch plate on either side of the said slot; and a foot lever fulcrumed in the said bracket and including a free end extending beyond the outer edge of the rail and a portion formed at right angles thereto extending through the said slot and engaging the rail.

2. A railway switch point lock comprising a latch plate extending under the rail and terminating in a vertically disposed flange having an inwardly extending slot, said flange adapted to be positioned in abutting relation with the outer edge of the rail; a resilient spring member longitudinally adjustable on the latch plate and secured to the said switch point; and a foot lever pivoted to the said latch plate and including an arm extending beyond the edge of the rail and a portion formed at right angles thereto extending through the said slot and engaging the bottom of the rail.

3. A railway switch point lock comprising a latch plate adapted to extend below and to be positioned in abutting relation with the outer edge of the rail, a leaf spring member fastened to the

said latch plate and to the said switch point, and a foot lever pivoted to the said latch plate and adapted to engage the bottom of the rail to release the portion of the said latch plate abuttingly engaged therewith.

4. A railway switch point lock comprising a latch plate adapted to extend below and to be positioned in abutting relation with the outer longitudinal edge of the rail, a leaf spring secured to the said latch plate and to the switch point, means to longitudinally adjust the leaf spring with respect to the said latch plate, and a foot lever pivoted to the said latch plate and having a portion adapted to engage the underside of the said rail to release the portion of the latch plate abuttingly engaged therewith.

5. In combination with a railway rail and switch point, a latch plate adapted to extend under the said rail and terminating in a vertically disposed flange adapted to be positioned in abutting relation with the outer longitudinal edge of the rail, a holding bracket having one end longitudinally adjustably secured to the latch plate and with its other end thereof secured to the said switch point, a lever pivoted to the said latch plate and including a foot receiving portion and lever arm disposed at right angles thereto adapted to engage the underside of the rail and to disengage the vertically disposed flange portion of the said latch plate.

6. In combination with a railway rail and switch point, a locking member including a portion adapted to extend under the rail and terminating in a vertically disposed flange adapted to be positioned in abutting relation with the outer longitudinal edge of the rail, and a portion adapted to be secured to the said switch point to hold the said rail and switch point normally closed; and a lever pivoted to the said locking member and including a foot receiving end and a portion formed at right angles thereto adapted to engage the underside of the said rail to disengage the vertically disposed flange of the said locking member therefrom.

CHARLES M. STAPLES. 45
